(57) **CLAIM**

The ornamental design for a burglar alarm component, as shown and described.

DESCRIPTION

3.1 is a perspective view of our new design for a burglar alarm component.

3.2 is left side elevation view of Figure.3.1

3.3 is a bottom plan view of Figure.3.1

3.4 is a top plan view of Figure.3.1

3.5 is a second perspective view of Figure.3.1

3.6 is a front elevation view of Figure.3.1

3.7 is a rear elevation view of Figure.3.1

The features shown in broken lines in the drawing depict portions of the part of the burglar alarm component and form no part of the claimed design.
